[57] CLAIM

The ornamental design for handle for a utensil lid, as
shown.

DESCRIPTION

FIG. 1 is a top front perspective view of a handle for
utensil lid, showing my new design, with the utensil lid
shown in broken lines for illustrative purposes only;
FIG. 2 is a right end elevational view thereof, the left
end elevational view being a mirror image thereof;
FIG. 3 is a front elevational view thereof, the rear ele-
vational view being a mirror image thereof;
FIG. 4 is a top plan view thereof; and,
FIG. 5 is a bottom plan view thereof.

FIG. 1

FIG. 4

FIG. 3

FIG. 2

FIG. 5
